ATTORNEY

UNITED STATES PATENT OFFICE.

ROBERT J. MORLEY, OF ROCHESTER, NEW YORK.

CIGARETTE-PAPER.

1,363,989.

Specification of Letters Patent. Patented Dec. 28, 1920.

Application filed August 4, 1919. Serial No. 315,305.

To all whom it may concern:

Be it known that I, ROBERT J. MORLEY, a citizen of the United States, residing at Rochester, in the county of Monroe and 5 State of New York, have invented certain new and useful Improvements in Cigarette-Papers, of which the following is a specification.

The object of this invention is to provide 10 a cigarette paper with a pocket into which the tobacco can be poured and rolled up into it without spilling any of the tobacco.

This and other objects of this invention will be fully illustrated in the drawings, 15 described in the specification and pointed out in the claims at the end thereof.

In the accompanying drawings:

Figure 1 is a plan view of the cigarette paper blank.

20 Fig. 2 is a plan view of a modified form of the blank.

Fig. 3 is a perspective view of the cigarette paper with the pocket formed thereon.

25 Fig. 4 is a perspective view of the paper with the pocket, showing modified means for forming the pocket on the paper.

Figs. 5, 6 and 7 are sectional views of the 30 paper showing progressive positions of the paper while the tobacco is being rolled up into it to form a cigarette.

Fig. 8 is a perspective view of still another form of the paper and its pocket.

In the several figures of the drawing like reference numerals indicate like parts.

35 In rolling cigarettes by hand invariably some of the tobacco is spilled while pouring it into the trough formed by the paper that is now being sold for this purpose. In order to obviate this waste of tobacco the present 40 invention is provided with a pocket into which the tobacco can be poured without spilling any of it.

The blank 1 from which the cigarette is 45 made has the short extensions 2 and 3 provided thereon, one on each end thereof. The blank 1 is folded the full length thereof along the dotted line marked 4 which passes through the middle of both the extensions 2 and 3. After being folded together in this 50 manner, the halves of the extensions are pasted or otherwise suitably fastened together to form the pocket 5 as shown in Figs. 3, 4 and 8. One side of this pocket is left to project beyond the other side of the 55 pocket for a purpose that will presently appear.

The long side 6 of the pocket has a straight edge formed thereon, which edge is parallel with the bottom of the pocket while the other side 7 is provided with a curved 60 edge which is high in the middle and gradually curves down on each side thereof.

To roll a cigarette with one of the papers the pocket 5 is opened up and the tobacco 65 poured into it as shown in section in Fig. 5. The closed ends of the pocket prevent the tobacco from falling out at the end of the pocket as the tobacco drops into it. After the pocket has thus been filled, the curved side of the pocket is gradually turned in toward the side 6 and in doing so is folded 70 over the tobacco.

The fact that the sheet 7 of the blank side is higher in the middle makes it possible to fold this side into the pocket without crumpling the ends thereof while doing it. This 75 is due to the fact that while the middle of the side 7 begins to fold over the pocket immediately on the turning over of the side, the ends thereof enter into the pocket in 80 back of the tobacco gradually but not until the middle thereof has been completely folded over the tobacco.

After the short side has been folded over the tobacco as above pointed out, the longer 85 side 6 is folded back over the short side 7 as shown in Fig. 7, in which position both of the sides may be fastened together by means of a suitable adhesive in order to give the cigarette thus formed the circular cross section shown in Fig. 7.

The outline of the blank for the cigarette paper may be modified as shown in Fig. 2 in which the extensions 2 and 3 are omitted. This form of blank forms a cigarette paper 95 as shown in Fig. 8, in which the sides 6 and 7 are directly fastened together instead of by suitable extensions formed on the ends thereof.

I claim:

1. A cigarette paper comprising a single sheet of paper, a portion of said sheet being folded back over the sheet, the sides of said folded portion of said sheet being fastened to the sides of said unfolded portion of said 100 paper to form an elongated pocket.

2. A cigarette paper comprising a single sheet of paper, said sheet of paper being folded to form a pocket having a long side and a short side, said short side being provided with a curved edge having a high 110 middle portion tapering down on each side

thereof, the ends of said pocket being closed by means of an adhesive.

3. A cigarette paper comprising a single sheet of paper, said paper having short extensions on each end thereof, said sheet of paper with its extension being adapted to be folded together to form a pocket having a long side and a short side, said folded extensions being fastened together to close 10 the ends of said pocket formed by said

paper, said short side of said pocket being higher in the middle than on each of the ends.

4. A cigarette paper comprising a single sheet of paper, said sheet of paper being 15 folded to form an elongated pocket having a long and a short side.

In testimony whereof I affix my signature.

ROBERT J. MORLEY.
